UNITED STATES PATENT OFFICE.

CARL HOLMCRANS, OF BOSTON, AND CARL GUSTAF BERGSTROM, OF EVERETT,
MASSACHUSETTS.

CATCH FOR POCKETS.

1,079,411.

Specification of Letters Patent. Patented Nov. 25, 1913.

Application filed February 27, 1911. Serial No. 611,293.

To all whom it may concern:

Be it known that we, CARL HOLMCRANS and CARL G. BERGSTROM, citizens of the United States, residing at Boston, county 5 of Suffolk, Commonwealth of Massachusetts, and Everett, county of Middlesex, Commonwealth of Massachusetts, respectively, have invented certain new and useful Improvements in Catches for Pockets, of 10 which the following is a specification.

This invention relates to catches and particularly to a pocket catch for securing that part of a garment against accidental or malicious opening.

15 The usual pocket, as formed in wearing apparel, is a notoriously unsafe receptacle for any article of value. This is due partly to the fact that a pocket, having cloth walls is of necessity rather a flimsy affair and liable even in the most carefully constructed 20 garments to sag or gape open. This either permits the accidental escapement of articles contained and their consequent loss, or makes easy the work of the pick pocket 25 whose art is as old as that of pocket making but which has been heretofore developed to a much higher degree of skill in practice and success in result.

It has been attempted to protect pockets 30 by flaps and even by buttons, but such constructions have not been anywhere near adequate either to overcome the liability to accidental loss or to foil the skill of the light fingers of the professional thief.

35 It is the object of our present invention to provide a catch which shall be capable of affording protection to a pocket and which shall be so simple in operation as to cause no annoyance to the user and which will be 40 effective in preventing loss from whatever cause. This we secure by providing inter-engaging means on the two faces of the pocket so related that the normal downpull of weight at the bottom of the pocket tends 45 to hold the same securely locked.

The construction and operation of our device will be more fully described in the specification which follows.

In the specification we have made reference 50 to a particular construction which we find well adapted to practical use. This embodiment we have illustrated in the drawings which form a part of the specification

and throughout specification and drawings like reference numerals are employed to indicate corresponding parts. 55

In the drawings:—Figure 1 is a diagrammatic view of a section of a pocket equipped with our device, Fig. 2 is a front view of the catch plate, Fig. 3 is a front view of 60 the socket piece, Fig. 4 is a central vertical section of the socket piece and catch piece engaged, and Fig. 5 is a transverse section of a socket piece.

1 and 2 are, respectively, the inner and 65 outer walls or faces of a pocket 3 formed in a garment 4.

5 is the edge formed between the outer wall 2 and the garment 4.

6 is a plate having marginal perforations 7 for stitching to the pocket wall and centrally of the plate is a head or T shaped catch piece 8. 10 is a rear plate having a spring tongue 11 struck up therefrom, while 12 is a front plate having a vertical T 75 slot 13 vertically disposed therein. The margins 13' of the slot 13 are turned down to form a pair of inwardly directed flanges. The spring 11 bears against the inner edges of these flanges 13' and presses yieldingly 80 against the same. The catch piece 6 is located slightly below the socket piece 12 and preferably has its headed catch 8 normally on the level of the bottom of the slot 13. In this way, when the pocket is in its 85 proper position the headed catch piece 8 may occupy its locked position in the bottom of the slot 13 without either a tendency to lift up on it or a drag on the socket.

In use, the edge of the pocket 5 would be 90 grasped between the thumb and fore finger and the pocket wall 2 slightly raised until the head catch 8 came opposite the cross slot at the top of the T slot 13. The headed piece 8 might then be inserted in the slot and 95 pushed down along the edges of the slot 13' until the end is reached. It is to be noted that the flanges 13' terminate just short of the bottom of the slot 13, thereby permitting the extension of the head 8 to drop behind the ends of the flanges 13' and be held there under the action of the spring 11.

To unlock the pocket the plate 6 is simply pressed inwardly until the headed portion of the catch piece 8 clears the edges of the 105 slots 13'; then, by raising the edge of the

socket 5 the catch 8 may be brought out through the top of the T slot and the pocket left free.

Various modifications may be made in the 5 structure and operation of our device, all without departing from the spirit of our invention if within the limits of the appended claim.

What we therefore claim and desire to secure by Letters Patent is:—

A catch of the class described comprising a catch plate having a catch member, a base plate having a resilient integral tongue struck up from the metal thereof 15 and inclined outwardly therefrom, a socket plate mounted on said base plate having a

T-shaped locking slot therein, in which said catch member is adapted to be engaged, in-turned bearing flanges formed on said socket plate along the sides of the stem part 20 of said T-shaped slot but terminating short of the end thereof against which flanges and beyond the terminals thereof the free end of said resilient tongue yieldingly bears.

In testimony whereof we have affixed our signatures, in presence of two witnesses.

CARL HOLMCRANS.

CARL GUSTAF BERGSTROM.
